UNITED STATES PATENT OFFICE

2.579.124

DETACHABLE BUTTON OR ORNAMENT

Vivian A. Patterson, Shreveport, La.

Application April 2, 1947, Serial No. 738,817

2 Claims. (Cl. 24—105)

The present invention relates to detachable buttons, ornaments and the like such as are used on apparel, fabrics and wherever such accessories are customarily employed and has more particular reference to a structural adaptation characterized by a screw-threaded fabric penetrating stud, a washer-like companion element detachably connectible to the stud, and a button connected to said washer-like element, the latter two parts, as a two-part assemblage, being unitarily attachable to said stud.

As implied in the preceding general statement of the invention, the idea of associating an ornament or button with an attaching member and then threading said member on a stud anchored on fabric is, of course, not new. In carrying out the principles of the instant invention the improvements relied upon are in the nature of nominal refinements which, it is believed, render the structure herein disclosed a novel and distinct contribution to the field of invention under advisement.

One improvement has to do with the adoption and use of a special assembling, stud retaining, and button anchoring member, this being of the aforementioned washer-like form and having a screw-threaded hole to accommodate the stud, additional holes to accommodate either wires or threads for attaching the button to said member, and marginal prongs on the latter which may be bent to assist, when wire is used, to hold the wire securely in place.

Another object of the invention has to do with the aforementioned washer-like member or part, the same having an outstanding prong to penetrate the fabric and to serve as an anchor and to prevent rotation of the button and member, unitarily pictured, in relation to the stud.

Other objects and advantages will become more readily apparent from the following description and accompanying illustrative drawings.

In the drawings, wherein like numerals are employed to designate like parts throughout the views:

Figure 1 is a perspective view showing a button wired to a coacting member forming a principal part of the complete assemblage.

Figure 2 is also a perspective view showing the same parts but illustrating the button up close to the washer-like member and further showing one of the marginal lugs bent, the other one being unbent. 50

Figure 3 is a fragmentary detail sectional view showing the manner in which all parts are assembled and mounted on a piece of fabric or the like.

2
Figure 4 is a perspective view illustrating a modified version of the invention.
Figure 5 is a view similar to Figure 3 but showing the modified version of Figure 4 in use.
5 Referring now to the drawings and particularly to the form of the invention illustrated in Figures 1 to 3 inclusive, the numeral 7 designates a suitable button or ornament having attaching holes 8 as usual. The holes may serve to accommodate a thread which is adapted to sew the button in place or, as here shown, may accommodate a length of bendable wire of appropriate gauge, the bent reaches 9 and 10 extending through the holes and being twisted together as 10 at 11. The aforementioned washer-like member is denoted, as an entity, by the numeral 12 and comprises a ring-like plate of appropriate material and dimensions as at 13, the same having a central screw-threaded bolt accommodating hole 15 14. At diametrically opposite points said member is provided with smaller holes, that is, holes to accommodate said wire, these holes being denoted by the numerals 15 and serving to permit 20 passage of the anchorable ends 16 and 17 in place. The terminal end portions 16 and 17 are adapted to be wrapped or otherwise secured against the body of the washer-like member 13 by 25 diametrically opposite V-shaped lugs 18 and 19. In Figure 2 I show the button drawn up close to the washer-like member 13, one of the lugs 18 30 being bent in to secure the wire end 17 in place. The other wire-end 16 is shown free, merely to illustrate the construction and principle of usage.

It is important to note that the washer-like member 13 constitutes a companion part of the adapter which applies to and is fastened on the cloth or fabric 20 as shown in Figure 3. Here, we see a pointed penetrating screw-threaded stud 21 carried by a stud backing plate or head 22. The stud is pushed through the fabric and the threaded end is threaded into the hole 14 thus clamping the two parts, the stud means and washer means together. It follows that these two parts are clamped on the cloth and the button is wired to the part 13. This gives the appearance of sewing the button to the garment or fabric but obviates the necessity of having to sew the stud means in place. In certain circumstances the sewing of buttons to garments is unhandy and therefore by providing the stud and its associate washer-like means 12, and wiring or otherwise permanently attaching the button to said part 12, an ideal assemblage is provided.

55 Instead of sewing the button or wiring it in place it is sometimes desirable to accomplish the expected result by using the modification.

shown in Figures 4 and 5. Here the pointed screw-threaded stud 23 is carried by head 24 and is fastened to the fabric 25. The button 26 has a centrally positioned concavo-convex boss 27 defining a recess on the rear or inner face of the button. This recessed face of the button is secured, as at 28 to the washer-like member 29. This member is slightly smaller in diameter than the member 13 and also smaller than the button. Structurally however, it is much the same as the member 13 in that it includes holes 15a which correspond to the holes 15, and includes a screw-threaded center opening 14a which corresponds to the feature 14 in Figures 1 and 2. And instead of using two V-shaped lugs three are employed and these are denoted by the numerals 19a and are clinched in place as shown in Figures 4 and 5. The idea is to provide interchangeable types of washer-like members having certain common characteristics. In this embodiment the washer-like member is provided with a marginal outstanding prong 30 which is adapted to penetrate the cloth or fabric 25 as shown in Figure 5 to prevent rotation of the button 26 and member 29 in relation to the stud 23. The parts 23 and 24 correspond to the parts 21 and 22 in Figure 3. The button is of any suitable type and is preferably of the form shown in Figure 5. The button is here, glued, cemented, soldered or otherwise rigidly fastened at 28 to the washer-like member. When thus soldered in place it is not necessary to use the holes 15a. Nor, are the bendable lugs 19a necessary in the arrangement of Figure 5; so, they are clinched in. The member 29 therefore becomes a solid part of the button and serves to detachably connect the button to the stud and also serves to prevent relative rotation through anchorage of the prong 30 in the fabric.

Changes in shape, size, materials and rearrangement of details and parts may be resorted to in actual practice, so long as they do not depart from the spirit of the invention or the scope of the appended claims, as is well understood.

I claim:

1. In a structural assemblage of the class shown and described, in combination, a piece of fabric, an apertured button, a washer-like member interposed between said button and fabric and provided at its center with a screw threaded hole constituting a nut, said washer-like member being provided with diametrically opposite auxiliary apertures, the latter being eccentric in respect to said screw-threaded hole and being further provided on its marginal edge portions

with diametrically opposite lugs registrable with said auxiliary apertures, a length of wire bent between its ends and having its end portions passing through the apertures in said button and then through the apertures in said washer-like member, said lugs being bent inwardly over the body portion of the washer-like member and the terminal portions of the wire-ends being wrapped around and secured to said lugs, and a screw-threaded stud having a head at one end, the head being in contact with one side of the fabric, said washer-like member being in contact with the other side of the fabric, said stud passing through said fabric and being threaded into said nut.

2. In a structural assemblage of the class described, in combination, a conventional-type button having apertures, a length of readily bendable and twistable wire having its intermediate portion in contact with the button and its end portions passing through and beyond the apertures in the button and twisted together adjacent the button, a flat-faced washer opposed in parallelism to a coacting side of the button, said washer being centrally formed with a hole and said hole being screw-threaded and constituting a nut, said washer being provided with a pair of diametrically opposite auxiliary openings located eccentrically in respect to said screw-threaded hole, said washer having its marginal portion provided with lugs in close associative proximity with said auxiliary holes, adjacent portions of the wire-ends passing through the auxiliary holes and being separably attached to said lugs, and a screw-threaded stud having a head at one end and having its opposite end pointed, the pointed end portion of the stud being screwed into said nut.
